Primary Examiner — Marianne N Pandozzi*(74) Attorney, Agent, or Firm* — Ladas & Parry LLP(57) **CLAIM**

I claim the ornamental design of a microwave oven tray with cover, as shown.

DESCRIPTION

FIG. 1 is a perspective view of the tray portion of a microwave tray and cover showing my new design, the remainder of the design removed for ease of illustration; FIG. 2 is a bottom plan view thereof;

FIG. 3 is a side view thereof, the design being symmetrical about a central axis;

FIG. 4 is a top plan view thereof;

FIG. 5 is a top plan view of the cover portion of the microwave tray and cover, the remainder of the design removed for ease of illustration;

FIG. 6 is a side view thereof the design being symmetrical about a central axis;

FIG. 7 is a bottom view thereof;

FIG. 8 is a side view thereof, the design being symmetrical about a central axis;

FIG. 9 is a top perspective view thereof;

FIG. 10 is a bottom perspective view thereof;

FIG. 11 is a top plan view of a microwave tray and cover;

FIG. 12 is a side view thereof, the design being symmetrical about a central axis;

FIG. 13 is a side view thereof, the design being symmetrical about a central axis; and,

FIG. 14 is an exploded perspective view thereof.

1 Claim, 7 Drawing Sheets(56)
